Primary Examiner — Antoine Duval Davis(74) *Attorney, Agent, or Firm* — Antonio Papageorgiou, Esq.; Lombard Geliebter LLP(57) **CLAIM**

The ornamental design for floor height gauge, as shown and described.

DESCRIPTION

FIG. 1 is a perspective view of one side and the top of the floor height gauge according to one embodiment of my new design;

FIG. 2 is a perspective view of one side and the bottom of the floor height gauge according to one embodiment of my new design;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The dashed lines shown in the drawings illustrate environmental structure and form no part of the claimed design.
